UNITED STATES PATENT OFFICE.

WILLIAM ELLERY, OF SAN FRANCISCO, CALIFORNIA.

SLEEPING BAG.

Application filed July 5, 1928. Serial No. 290,552.

This invention relates to improvements in sleeping bags.

The principal object of this invention is to provide means whereby the sleeping bag 5 is protected during transportation.

Another object is to provide means whereby dust, dirt and water are excluded from the ends of the bag when the same is in rolled condition.

10 A further object is to provide means whereby the same protection used for the bag serves as a protection for the occupant's clothes while lying within the bag.

A still further object is to produce a device which is economical to manufacture and one which does not add materially to the cost of the bag.

Other objects and advantages will be apparent during the course of the following 20 description.

In the accompanying drawings forming a part of this specification and in which like numerals are employed to designate like parts throughout the same,

25 Figure 1 is a side elevation of a sleeping bag as the same appears when in unrolled condition and showing in dotted line the protector as the same may be used when occupied,

30 Figure 2 is a top plan view of Figure 1 showing the bag and protector in fully spread condition,

Figure 3 is a side elevation of the bag showing the bag portion rolled and about to 35 be encased in the protector the dotted lines of this figure show the position the protector is to assume, and

Figure 4 is a perspective view showing the appearance of the bag within the protector.

40 At the present time sleeping bags and the like outdoor equipment is merely rolled from end to end, straps or rope placed thereabout and then the same is either transported in this condition or further protected by inserting in a dunnage bag. Applicant has

45 provided means integral with the bag whereby the same is amply protected during transit and further through this arrangement applicant has eliminated the necessity for 50 an additional dunnage bag.

In the accompanying drawings wherein for the purpose of illustration is shown a preferred embodiment of my invention, the numeral 5 designates what is commonly

55 called a sleeping bag which consists of an elongated envelope shaped pocket which is

properly padded so as to protect the user against chill when resting therein. As the bag 5 forms no part of my invention further reference thereto, as far as construction is concerned, will be omitted.

To the open end of the bag 5 I secure a strip of fabric 6 which is of sufficient length to make one single wrapping about the bag 5 when the same is in rolled condition. To this fabric 6 I attach side flaps as shown at 7 and 8 each one of which is folded upon itself and stitched as at 9 and 11 respectively, thus forming tubes through which the cords 12 and 13 are laced.

The result of this construction is that when the bag 5 is rolled as illustrated in Figure 3, the same is rolled from the bottom of the bag toward the top with the result that the strip of fabric 6 will completely surround the bag and protect the same. By now pulling on the opposite ends of the cords 12 and 13 individually, the side pieces 7 and 8 will be gathered as illustrated in Figure 4. This gathering completely encloses the end of the bag thus protecting it against dust, rain and other dirt which might otherwise come into engagement therewith.

Fastening means may be employed as shown at 14 and 16 the purpose of which is obvious. It is of course understood that the same construction might be employed with other camping equipment such as the tent without departing from the spirit of the invention.

It will thus be seen that I have produced in a very simple manner, a means whereby an article of camping equipment may be quickly and completely enclosed and protected against damage which is not now possible without employing a separate dunnage bag which is bulky, heavy and causes additional weight far beyond that of applicant's device.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:

The combination with a sleeping bag made from flexible material adapted to be

rolled into a cylindrical body, said bag being open at the head end, a fabric wrap-
per strip secured by one end edge portion to
the open end of the bag and having a length
5 sufficient to entirely surround said bag upon
the latter being rolled up, said strip being
of greater width than the bag to provide
side extensions at each side of the bag, the
respective side edge of each side extension
10 being provided with a draw string having
both ends projecting to form a pair of strip

securing strings, the widths of said side ex-
tensions being sufficient to enclose the re-
spective ends of the rolled bag when gath-
ered by said draw strings, said draw strings 15
thereby serving to draw the side extensions
over the ends of the rolled bag and afford-
ing means whereby the several corners of
the fabric strip may be attached to fixed
objects to form a weather shield.
